Primary Examiner — Sandra Snapp*(74) Attorney, Agent, or Firm* — Merchant & Gould P.C.**CLAIM**

The ornamental design for furniture, as shown and described.

DESCRIPTION

FIG. 1 is a front perspective view of furniture showing our new design;

FIG. 2 is a rear perspective view thereof;

FIG. 3 is a front elevational view thereof;

FIG. 4 is a rear elevational view thereof;

FIG. 5 is a left side elevational view thereof, a right side elevational view not being shown as it is a mirror image thereof; and,

FIG. 6 is a top plan view thereof.
